ELECTRON DISCHARGE DEVICE CIRCUIT

Walter van B. Roberts, Princeton, N. J., assignor
to Radio Corporation of America, a corporation
of Delaware

Application October 7, 1935, Serial No. 43,880

7 Claims. (Cl. 178—44)

This invention relates to electron discharge device circuits, and more especially concerns such circuits which are adapted for use with electric cables, particularly the high frequency coaxial 5 conductor type of cable.

In the past, in using long cables for the transmission of messages, it has been customary to employ repeaters at predetermined intervals along the cable to amplify the message waves to overcome losses due to attenuation, leakage, etc. 10 These repeaters, which may be either of the electron discharge device or magnetic relay type require complicated and expensive circuit arrangements for obtaining any sort of amplification of 15 the signals which is uniform over a wide range of frequencies. Another disadvantage of the foregoing types of repeaters is that they cannot be inserted in the transmission path without the use of very carefully arranged terminating 20 resistances. A further disadvantage of these known repeaters is that the transmission of signals along the cable is interrupted in the event of failure of the amplifying properties of the apparatus.

25 The present invention is designed to overcome the foregoing disadvantages and has for one of its objects to provide a more economical installation for amplifying a wide band of frequencies. A further object is to provide an amplifier which 30 is adapted to be actually inserted in a transmission line for overcoming the energy losses of the line. A still further object is to provide a transmission line having a negative damping characteristic for the production of sustained oscillations of a wave length determined by the length of 35 the line.

An important advantage of the present invention is that in case of failure of an amplifier constructed in accordance with the principles there- 40 of, signals are nevertheless transmitted there- through without appreciable loss, although of course without the gain characteristic of the amplifier in its normal condition.

In brief, the invention comprises an "expander 45 line" (exhibiting a negative conductance) which is adapted to be actually inserted in and as a portion of the transmission line. According to one embodiment of the invention, there is employed as an amplifier an expander line section 50 comprised of a network of series impedances having connected thereacross a pair of serially connected electron discharge devices providing negative conductance properties. This section is constructed to have a characteristic impedance to 55 match the line in which it is inserted. Accord-

ing to another and preferred embodiment, the amplifier is an electron discharge device having elongated electrodes, possessing distributed negative conductance characteristics and functioning by dynatron action, which is made to act as a concentric transmission line. A third embodiment of the invention is a double cold cathode device exhibiting negative resistance effects. A fourth embodiment illustrates the manner in which any of the first three embodiments can be used in a receiving circuit.

Other objects, advantages and features will appear from a reading of the following detailed description which is accompanied by drawings, wherein:

Figs. 1 and 2 show, by way of explanation only, well known types of sections of smooth and lumped transmission lines, respectively;

Fig. 3 illustrates a section of expanding line for amplifying signals, in accordance with one 20 embodiment of the present invention;

Fig. 4 illustrates a cross-section of a portion of a transmission line of the two conductor or coaxial type, equipped with an expanding line section, in accordance with another embodiment 25 of the present invention for obtaining distributed negative conductance;

Fig. 4a is a transverse cross-sectional view of the expanding line section of Fig. 4, along the lines 4a—4a;

Figs. 5 and 6 show cross-sectional views of other expanding line sections, in accordance with the principles of the present invention, for obtaining distributed negative conductance along the section; and

Fig. 7 discloses a centralized radio receiving system containing an expanding line section, in accordance with the invention.

Fig. 1 illustrates an ordinary well known type of transmission line, for example, a two-wire line adapted to transmit a wide band of frequencies. In such a line the series inductance and resistance, and the shunt capacity and shunt or leakage conductance are uniformly distributed along the line. The damping coefficient of such a line is given by the equation:

$$\frac{1}{2}r\sqrt{\frac{c}{l}} + \frac{1}{2}k\sqrt{\frac{l}{c}} \quad (1)$$

where

l = inductance per cm. of line,

r = resistance per cm. of line,

c = capacity per cm. of line,

k = leakage conductance per cm. of line,

and k and r are small, and the frequency f is low. It is well known that a line composed of sections having lumped constants as shown in Fig. 2, acts exactly like a line having distributed constants in Fig. 1 for frequencies so low that there are a considerable number of such sections per wave length on the line. If such sections are designed to have a characteristic impedance equal to the characteristic impedance of the smooth line, then such sections may be inserted in the smooth line without reflection losses and will act substantially like the smooth line for the above mentioned frequencies commonly referred to as the frequencies below cut-off of the section shown in Fig. 2.

It will be noted from Equation 1 that k is made negative and sufficiently large in value, the damping coefficient given by this equation will become negative, and signals passing through the line will increase in energy as they go along rather than decrease as they do in the ordinary dissipative type of line.

Fig. 3 shows how, in accordance with one embodiment of the invention, a negative conductance may be shunted across the capacity of the section shown in Fig. 2. In Fig. 3 a pair of tubes T, T are connected so that the excitation of the grid G of each tube is opposite in phase to the potential on the plate P of the tube, thus resulting in a negative conductance across the line of a magnitude given approximately by the formula:

$$-\frac{1}{2}\mu/R, \quad (2)$$

where μ is the amplification constant and R , the internal resistance of the tube. This equation may be readily derived as follows: If the grid of a tube is excited in opposite phase to its plate and with equal voltage, and the amplification constant μ is large compared to unity, the plate circuit will exhibit negative conductance substantially equal to the mutual conductance of the tube. Since two such tubes are connected in series across the line if Fig. 3, the negative conductance will obviously be one-half of this value. From Equation 1 it may be seen that an expansion of the signals passing through the section Fig. 3, will occur when the mutual conductance of the individual tube is more than twice the series resistance of the section divided by the square of the characteristic impedance of the section or line; in other words, if the characteristic impedance of the line

$$\mu = \sqrt{I/c},$$

then negative damping occurs if

$$\mu/R_s > 2\frac{r}{\mu}$$

Modern amplifier tubes have mutual conductance far greater than necessary to produce this expanding action. (Hence it is preferable to use very small tubes with small capacities and exciting currents, and designed for long life.) Therefore, if a section as shown in Fig. 3 and constructed with a characteristic impedance to match a given line is inserted in the line, it will make up for the loss in a considerable length of the line. Thus, by inserting such sections at intervals along a transmission line, the signals travelling along it may be prevented from becoming weaker at the receiving end. The shunt capacity of Fig. 3 may, if desired, consist solely of the tube capacities.

An important advantage of this method of

amplifying signals as contrasted with the ordinary known type of vacuum tube repeater for inserting gain in a long line is that whereas the ordinary repeater completely interrupts the transmission of signals when a repeater fails, for example due to tube failure, the expander section, Fig. 3, in accordance with the invention, does not interrupt the passage of signals in case of tube failure but allows the signals to continue to pass therethrough exactly as they traverse any portion of the ordinary line. Hence, if each expanding section is designed for only a small amount of gain, failure of one section will merely cause the signals arriving at the line terminals to be a small amount weaker than normal, which amount can be made up by a little additional gain at the terminals of the line.

In Fig. 3 resistance r'' and capacity c'' provide grid bias in the usual fashion in connection with grid leaks r' . Condensers c' are blocking condensers, and chokes x are provided to allow energization of the tubes with the necessary direct current from battery B. One direct current energization connection to the line is all that is necessary for all the expanding sections, provided the line is otherwise insulated from ground.

For very high frequency signals it would be necessary to use impractically small tubes and numbers of sections if the method of Fig. 3 were to be attempted, and consequently for such ultra high frequencies, the arrangement of Fig. 4 is preferred.

Fig. 4 shows to the left and right of the vertical dotted lines V, V and V', V', respectively, sections of what is commonly called a co-axial concentric transmission line consisting of a circular outer conductor O with a circular inner conductor I coaxial therewith. For a more detailed description of various types of coaxial lines, reference is herein made to United States Patent No. 1,978,418, granted to H. W. Dudley, October 30, 1934.

Between the vertical dotted lines, is the preferred form of amplifier of the invention, comprising a portion of a geometrically similar concentric transmission line arranged to have distributed negative conductance between an inner conductor S and the coaxial outer conductor A. This arrangement comprises an electron discharge device having an evacuated glass envelope E containing within it an outer conductor A, an inner co-axial conductor S in the form of a grid, and an indirectly heated cathode C. If desired, part of the envelope E may be dispensed with and the outer conductor A used as part of the envelope. Conductor A may be made to be an extension of the outer conductor O of the dissipative line, and conductor S an extension of I. Fig. 4, except that inner conductor S is made of a bundle of conductors parallel to the axis of the structure or may be formed as a cylinder of wire mesh. In other words, conductor A may be made to have, if desired, the same diameter as O and conductor S the same diameter as I. Within the inner conductor S lies an indirectly heated cathode C. Conductor S is maintained at a high average positive potential by connection through a choke to a battery B' while outer conductor A is maintained at a lesser average positive potential. Thus, by means of secondary emission of electrons from outer conductor A there is made to appear between conductors S and A a negative conductance. This effect, as well as suitable values of voltage for producing it, is well known in ordinary tube structures as dynatron action. Ac-

cording to the present invention, however, the system of Fig. 4 is made to act as a concentric transmission line and the negative conductance distributed along it produces an expanding action upon signals travelling therealong. Its action is identical with that described in connection with Fig. 3 except that in this case, since there are no lumped constants, there is no cut-off frequency until the frequency becomes so high that electron time of flight interferes with the production of sufficient negative conductance to provide the required expanding action. In practice, it is preferred to provide a large capacity indicated at K but distributed all along between cathode C and inner conductor S so as to assure that no large radio frequency differences of potential exist between them. A single set of batteries B' may be employed for polarizing the electrodes of several expander line evacuated sections located at intervals along the coaxial transmission line O, I, and, if desired, blocking condensers N, N' may be employed to prevent direct current voltage being impressed on the conductors of the coaxial line. It is only necessary that the characteristic impedance of the expander section shall be the same as that of the rest of the line. Since the characteristic impedance depends only upon the ratio of the inner diameter of the outer conductor A to the outer diameter of the inner conductor S, it is obvious that the expander section may be made physically similar to or larger or smaller, according to convenience, than the rest of the line and yet be inserted in the line without reflection of signals as they pass from the expander section to the ordinary line, or vice versa. In other words, expander sections of the sort shown in Fig. 4, between the vertical dotted lines, do not need to be made identical in dimension with the coaxial transmission line into which they are inserted.

As mentioned in connection with Fig. 3, the negative conductance available from dynatron action in ordinary tube structures is greatly in excess of the value required to produce expansion characteristics. Thus a relatively short section of expander line will make up for the losses of a much longer section of ordinary line. On the other hand, if in practice it is found preferable to utilize a cathode having far less emission than ordinarily provided in vacuum tubes, the entire line may be constructed of the expander type, but with the emission so small that the negative conductance effect merely balances out the natural dissipation of the line.

Fig. 4a shows a cross-section of the expander line of Fig. 4 along the line 4a—4a.

Fig. 5 shows a cross section of a balanced transmission line built in the form of a pair of elongated vacuum tube structures acting in principle like Fig. 3 but providing a distributed negative conductance along the line. The line proper consists of two plates or strips of conductor A', A' which also act as anodes cooperating with a central cathode C', preferably of the indirectly heated type. Capacities K' are provided, preferably in continuous manner, but in any case at frequent intervals along the length of A', A' compared to the wave length employed, between the grid structures G' controlling the current to one side of the line, and the other side of the line, in order to energize the grid G' at every point in opposite phase from the potential of its cooperating adjacent plate A' at the corresponding point. The continuous capacity K' may take the form of 75 closely adjacent plates extending throughout the

length of the anodes and grids. Grid leaks GL, G'L' are also provided, and a cathode resistor or bias battery may be employed for bias. The direct current connections are only required at one point in the expander line, which may be anywhere along the line. The two plates or line conductors A', A' are maintained at an average positive potential by a battery B, B through choke coils L', L'. In this case the negative conductance per unit length of line is again equal to approximately one-half the mutual conductance per unit length of each tube structure. The section of line in accordance with the cross section of Fig. 5 may be used interchangeably with the type of section shown in Fig. 3 but with the added advantage that, like the structure of Fig. 4, it has no inherent cut-off frequency. In Fig. 5 a pair of grounded strips P are run parallel to the cathode to reduce the control action of one grid upon the other plate. These strips, if desired, may be connected at frequent intervals to the cathode. A screen structure at positive potential could, if desired, be employed for the same purpose, or separate cathodes could be used with screening or space between them to prevent cross control action of one grid on the plate current from the cathode of the other tube structure. The cathode c', of course, must be connected to ground at least one point.

The methods of connecting a symmetrical or balanced line to an unsymmetrical line such as the concentric co-axial type, are well known and need not be discussed here, since they form no part of the present invention per se.

Fig. 6 shows a cross section of an elongated structure designed to operate as a two-wire transmission line. This structure consists of an evacuated envelope E containing within it two pairs of oppositely disposed metallic strips or electrodes D, D and F, F, the envelope being immersed in an electromagnetic field produced by coil M. This device may be given a negative conductance characteristic between the two sides of the line D, D by coating conductors D, D with electron emissive material so as to produce secondary emission from impact by primary electrons, applying a high positive potential to the collector strips F, F from a battery B, and connecting the two sides of the line D, D in the manner shown in the drawings.

The operation of the system of Fig. 6 is as follows: An electron from one conductor D, which applicant chooses to call a dynode, will be attracted toward the other dynode D with velocity increasing at first due to the accelerating influence of positively charged collector strips or anodes F, F, and then decreasing after passing the central position of strips F, F due now to their decelerating influence, until it strikes the other dynode, whereupon it will splash out other electrons and they will be attracted back to the first dynode and thus continue to oscillate back and forth with a frequency determined by the distance between the dynodes D, D and the voltage of battery B, until they ultimately drift over to the collector strips F, F. A strong magnetic field extending between the two dynodes caused by coil M surrounding envelope E, and acting parallel to the motion of the electron, will tend to prolong these oscillations and prevent the electrons reaching the collector strips F, F until after several back and forth trips between the dynodes.

In the foregoing, it has been assumed that an alternating voltage is impressed between dynodes from an outside source O', as shown, and if the 75

frequency of this voltage is substantially the same as the frequency of electron oscillation, then starting from a few electrons, such as are always emitted by photoelectric action from the dynodes, the number of electrons oscillating within the tube will be built up by secondary emission from the dynodes produced by the applied alternating voltage until a considerable average current flows through milliammeter I'. It has been determined 10 experimentally that as the voltage B' is increased, there will be a value of voltage where further increase in voltage causes a decrease of current through I'. This decrease constitutes a negative resistance with respect to the points to which the battery is connected. This negative 15 conductance is the sum of the negative conductance between the collectors F, F and the two dynodes D, D, so that there exists between the two dynodes themselves a negative conductance 20 equal to one-quarter of the negative conductance presented to the battery. This is because two conductances arranged in series have one-quarter the value of the two conductances in parallel. Thus far we have considered only a short length 25 of structure of the cross section shown in Fig. 6, which together with its method of operation is known in the art.

In accordance with the present invention, the 30 structure whose cross section is shown in Fig. 6 is elongated to any convenient length and is utilized as a portion of a transmission line just as described with reference to Fig. 4, or Fig. 5, since it has the property of presenting a negative 35 conductance between the two sides of the line, which conductance is uniformly distributed over the full length of the line. In Fig. 6, small bypass condensers c''' are provided to permit the 40 ultra high frequency exciting voltage to reach the dynodes but which are too small to form an easy path for the relatively low frequency currents to be transmitted along the line. These condensers are shunted by choke coils X to provide a direct 45 current path. The battery and high frequency connections need only be made to one point on the expander line as both the direct voltage and the exciting voltage travel all over the line. The 50 phase of the high frequency exciting voltage is immaterial for the production of the negative conductance, and, therefore, this negative conductance will be produced throughout the entire length of the structure. The advantage of the arrangement shown in Fig. 6 is that it is unnecessary 55 to provide any source of initial electron emission such as a hot cathode, although it would be preferable to treat the surfaces of the dynodes D, D with a radio-active material or otherwise provide a reliable source of a few electrons for starting the action which results in the negative 60 conductance. Just as in the case of all the other amplifying arrangements here disclosed, the advantage is retained that in the case of failure of the negative conductance the signals continue, nevertheless, to pass along the expander line without appreciable diminution, although, of 65 course, without the intended gain.

The expander line of the invention may be utilized for connecting a signal pick-up device such as an antenna, to a terminating resistance such as the input of a radio receiver, with the 70 result that all radio frequencies picked up by the antenna will be equally amplified, thus reducing the amount of gain that must be provided in the receiver. In this case also, if the amplifier fails to function, the signals received on the antenna 75 will be transmitted to the receiver, although with-

out amplification. Fig. 7 shows such an arrangement, and this differs from well known practice only in the substitution of applicant's expander line section for the radio frequency amplifier unit. This figure shows a centralized radio receiver 5 system for use in hotels or apartment houses, wherein a plurality of receivers may be connected to a single antenna through branch lines connected to a common amplifying system.

While the invention has its primary application to long lines for transmitting a wide band of frequencies not exceeding low radio frequencies such as the modulation frequencies of television programs, the method of amplification disclosed may be employed for many other purposes. 10 For example, if an arbitrary length of expander line is terminated reflectively, waves originating from random infinitesimal disturbances will travel back and forth over it with increasing amplitude, thus setting up sustained oscillations 15 of a wave length determined by the length of line employed. As an illustration, if the line is open at both ends, the wave length will be twice the length of the line. By utilizing a large structure adapted to have very small inherent losses, the frequency 20 stability of such an oscillator may be made very great and the wave length generated will not be altered by the connecting of additional tube capacities across the line as is the case in present 25 practice. Such an arrangement is particularly 30 advantageous where frequencies to be generated are so high that the capacity effects of ordinary tubes attached to ordinary resonant lines seriously 35 affects the generated frequency.

What is claimed is:

1. A transmission line section comprising two terminals each having in series therewith concentrated impedances, and electronic means for producing negative shunt conductance across said terminals, said means including a pair of 40 electron discharge devices each comprised of anode, cathode and grid electrodes, the anode of each device being directly coupled to one terminal and capacitively coupled to the grid of the associated device and to the other anode, 45 the cathode of said devices being connected together, means for exciting the grid of each device in opposite phase to the potential of its co-operating anode, the mutual conductance of each device being greater than twice the series 50 resistance of the line section divided by the square of the characteristic impedance of the line section.

2. The combination with a plurality of serially arranged sections of transmission line each having substantially uniformly distributed series inductance and resistance and shunt capacity at the frequency of operation, of a pair of electron discharge devices connected in series across each section of line, means for exciting the grid of 55 each tube in opposite phase and with substantially equal voltage to the anode thereof, where-by each tube exhibits negative conductance, the magnitude of negative conductance of each tube being greater than twice the series resistance of 60 the associated section of line divided by the square of the characteristic impedance of the section of line.

3. The combination with a section of transmission line having substantially uniformly distributed series inductance and resistance and shunt capacity at the frequency of operation, of a pair of electron discharge tubes connected in series across said section of line, each of said tubes having an amplification constant large 70

75

- compared to unity and including a grid and an anode, means for exciting the grid of each tube in opposite phase and with substantially equal voltage to the anode thereof, whereby each tube exhibits negative conductance substantially equal to the mutual conductance of the tube, the magnitude of the mutual conductance of each tube being greater than twice the series resistance of the section of line divided by the square of the characteristic impedance of the section of line.
4. The combination with a plurality of serially arranged sections of transmission line each having substantially uniformly distributed series inductance and resistance and shunt capacity at the frequency of operation, of a pair of electron discharge devices connected in series across each section of line, means for exciting the grid of each tube in opposite phase and with substantially equal voltage to the anode thereof, whereby each tube exhibits negative conductance, the magnitude of negative conductance of each tube being greater than twice the series resistance of the associated section of line divided by the square of the characteristic impedance of the section of line, said sections each being designed to have a characteristic impedance which matches the impedance of the line into which it is inserted.
5. A transmission line section comprising two terminals each having in series therewith concentrated impedances, and electronic means for producing negative shunt conductance across said terminals, said means including a pair of electron discharge devices each comprised of anode, cathode and grid electrodes, the anode of each device being directly coupled to one terminal and capacitively coupled to the grid of the associated device and to the other anode, the cathode of said devices being connected together, means for exciting the grid of each device in opposite phase and with substantially equal voltage to the potential of its cooperating anode, the mutual conductance of each device being greater than twice the series resistance of the line section divided by the square of the characteristic impedance of the line section.

6. A line section adapted to be serially inserted in a two conductor transmission line, said section being only a fraction of the wavelength at the highest operating frequency and having distributed series inductance and resistance and negative shunt conductance in the form of electronic means, said electronic means comprising a pair of electron space paths in series, said paths, when electrically conductive, having sufficient negative shunt conductance to offset at least a portion of the damping of said line, said section having substantially the same characteristic impedance as said transmission line when said electronic means is not electrically conductive, the magnitude of negative conductance per unit length of each space path being approximately one-half the mutual conductance per unit length of line section.
7. A balanced transmission line section having negative attenuation and adapted to be inserted in a dissipative transmission line to offset a part of the attenuation thereof, comprising series and shunt impedance elements arranged to provide a passive transmission line section of predetermined characteristic impedance, a cathode element symmetrically disposed between both sides of said balanced line section, means for causing a flow of electrons from said cathode to each of said sides, a grid in each of the last-named electron flow paths for controlling the magnitude of the electron flow therein, and an alternating current connection from each of said grids to that side of the line section whose electron current is controlled by the other of said grids, the mutual conductance between each of said grids and that side of the line section whose current is thereby controlled being sufficient to render the resultant damping of said section negative, the total mutual conductance in said section between each of said grids and that side of the line which it controls being greater than twice the total series resistance of said section divided by the square of the characteristic impedance of said section.

WALTER VAN B. ROBERTS.
